ELECTROCUTING TRAP FOR FLYING INSECTS

Donald E. Gilbert, Jonesboro, Ark., assignor to Gilbert
Electronics, Inc., Jonesboro, Ark.

Filed May 7, 1971, Ser. No. 141,460

Term of patent 14 years

Int. Cl. D22—06

U.S. Cl. D22—19

FIG. 1 is an isometric view of an electrocuting trap for flying insects embodying my invention;

FIG. 2 is a rear view of FIG. 1;

FIG. 3 is a bottom view of the trap;

FIG. 4 is a view looking at the opposite end of the trap from that shown in FIG. 1;

FIG. 5 is a transverse sectional view taken along lines 5-5 in FIGS. 1 and 2, and

FIG. 6 is a longitudinal sectional view taken along lines 6-6 in FIGS. 1 and 5.

I claim:

The ornamental design for an electrocuting trap for flying insects, as shown.
